DIRECTIONAL INSTRUMENT

Paul Kollsman, Stamford, Conn., assignor, by
means assignments, to Square D Company,
Detroit, Mich., a corporation of Michigan

Application July 7, 1938, Serial No. 217,994

7 Claims. (Cl. 33—222)

This invention relates to improvements in directional instruments, more particularly to directional instruments for determining the direction of travel of movable craft.

Among other objects this invention aims to provide an improved directional instrument, more particularly a magnetic compass, having a substantially vertical dial and being so constructed as to permit mounting of the instrument on an instrument panel or other fixed part of an airplane or speedboat with the dial in a fixed substantially vertical position without the necessity of employing the conventional gimbal mounting commonly used for suspending compasses. It is an object of this invention, accordingly, to provide an improved directional instrument which can be rigidly mounted on a fixed part of the craft in a similar manner as other control instruments, such as pressure gages, speedometers, temperature indicators, and the like.

It is a further object of this invention to provide in a magnetic compass a directional magnetic element mounted for freedom to turn about, and tilt relatively to, a substantially vertical axis, together with means for actuating an indicator in true response to the magnetic north-south direction to which the magnetic element responds.

More specifically, this invention aims at providing in a magnetic compass in combination with a directional magnetic element an improved magnetic pick-off actuated through magnetic confinement by the directional element and transmitting directional movements to an indicator, the magnetic pick-off being so constructed that no error will be introduced into the directional indication even upon relatively large tilting of the compass casing.

It is a further object of this invention to provide in a directional instrument, operating on any of the various well-known principles of directional indication, improved indicating means, permitting steering of a predetermined course as well as permitting a precise determination of deviations from said predetermined course.

Further aims, objects and advantages of this invention will appear from a consideration of the description, which follows with the accompanying drawings, showing for purely illustrative purposes an embodiment of this invention. It is to be understood, however, that the description is not to be taken in a limiting sense, the scope of this invention being defined in the appended claims.

Referring to the drawings:

Figure 1 is a front elevation of an improved compass according to this invention.

Figure 2 is a sectional side elevation of the instrument shown in Figure 1, a section being taken on line 2—2.

Figure 3 is a sectional front elevation on a reduced scale, a section being taken on line 3—3 of Figure 2.

Figure 4 is a sectional front elevation of the instrument shown in Figure 2, a section being taken on line 4—4.

Figure 5 is a diagram illustrating the operation of the magnetic pick-off.

Figure 6 is a perspective illustration of an improved directional element in combination with a positional pick-off according to this invention.

An instrument casing is shown in the illustrated embodiment as consisting of a front part 10 and a rear part 11, the front part being provided with a flange 12 for fixedly mounting the instrument on an instrument panel in a conventional manner, mounting screws 13 being shown for this purpose. The instrument thus partakes of all movements of the craft about the three principal axes, a vertical or azimuth axis, a longitudinal, and a lateral axis.

The front part 10 is provided with extensions 14 and 15 serving as a support for the direction responsive element.

In the form of the invention, shown in the drawings and illustrating a magnetic compass, the direction responsive element comprises a first or directional magnetic element 16 mounted within a float 17, the float being provided with a pivot 18 resting in a cup-shaped jewel bearing 19. The jewel bearing is mounted in an upper receptacle of a supporting stem 20 slidable in a sleeve 21 and mounted on the supporting bracket 14. A helical spring 22, bearing against the receptacle of the stem 20, resiliently supports the float thus preventing possible damage to the delicate jewel bearing in cases of shock exerted on the instrument. The directional element is thus supported for freedom to turn about as well as tilt relatively to the vertical or azimuth axis 4—5.

A tubular extension 23, extending into the float 17 and fitting loosely around the cup-shaped receptacle for the jewel bearing 19, prevents a disengagement of the pivot and jewel in cases where the instrument is turned upside down.

A liquid-tight chamber 24, containing a fluid 25, encloses the float 17, the fluid thus buoyantly 55

supporting the float with the magnetic element, thereby reducing the weight of the magnetic element 16 exerted on the jewel bearing.

A conventional expansion chamber, shown in the illustrated embodiment as being a diaphragm box 26, may be provided to compensate for expansion and contraction of the fluid in response to changes in temperature.

For the purpose of deriving a directional 10 pulse from the fluid-enclosed directional element for actuating indicating means a positional pick-off is provided.

In the illustrated embodiment the positional pick-off comprises a second magnetic or follower 15 element 27 mounted on shaft 28, the shaft being rotatable in bearings 29 and 30, supporting the follower magnet 27 for freedom to turn about the azimuth axis 5-5.

The indicating means of the illustrated form 20 of instrument include a pointer 31 supported on a shaft 32 rotatable in bearings 33 and 34 for rotary movement relatively to a normally fixed dial 35, provided with a directional graduation 36. The pointer and dial are visible through a 25 front window 37 of the instrument casing, the front window of the illustrated instrument being also used for illuminating the dial by means of an electric bulb enclosed in a compartment 38, as disclosed more specifically in my Patent 30 #2,088,559, dated July 27, 1937.

A bevel gear 39 is secured to the shaft 32 meshing with a second bevel gear 40 on the vertical shaft 28.

The operation of the instrument, so far described, is as follows:

The directional magnetic element, supported for free movement in azimuth, will align itself with the direction of the earth's magnetic field by virtue of its confinement by the same. The 40 pivotal support of the directional element permits the element to maintain a horizontal position irrespective of tilting movements of the craft or the instrument casing. The second magnetic or follower element 27, being of much 45 smaller magnetic force than the directional element 16, is maintained in magnetic confinement by the same and tends to align itself with the directional element, thus repeating the movements of the latter in azimuth. The movements 50 of the follower element 27 are transmitted to the indicating means which thus give an indication of the magnetic north-south direction with respect to the direction of travel of the craft on which the instrument is mounted.

In order to permit steering of a predetermined 55 course without the necessity of reading the pointer 31 against the graduation on the dial, a reference member is provided cooperating with the pointer as well as the dial.

In the illustrated form of the invention an externally toothed ring 41 is rotatably supported within the front part 10 of the instrument casing. The ring 41 bears a reference mark 42 normally 60 cooperating with the pointer and bearing one or several reference lines suitably formed by wires 65 43 and 44 extending across the face of the dial. The ring 41 is adjustable coaxially with respect to the pointer by means of a knob 45 turning a gear 46 by means of a shaft 47, the gear meshing 70 with the teeth of the ring 41.

The operation and use of the reference means is, as follows:

Assuming a course of 15 degrees is to be maintained by the pilot of the craft, the reference 75 mark 42 is moved into the respective position

relatively to the dial, as shown in Figure 3, by turning the knob 45. The craft is then steered in such manner as to maintain the tip of the pointer 31 opposite the reference mark 42. In order to relieve the pilot from unnecessary eye-strain, naturally involved in observing the movements of the pointer relatively to a point of the graduation or a relatively small reference mark, the reference lines 43 and 44 are provided indicating the maintenance of the proper course by 10 parallelism with the pointer 31. If a deviation from the predetermined course occurs, the amount of deviation can be easily read on the dial without readjustment into a new position of the reference mark and lines. When it is necessary temporarily to steer a course different from the set course, for example, in the vicinity of an airport, the temporary new course can be easily steered by maintaining the pointer on the respective graduation mark of the dial in a similar 15 manner as heretofore the dial of a compass was read with respect to a lubber's mark.

It is a feature of this invention that no resetting of the reference means is required in cases where a predetermined course is to be 20 steered temporarily different from the course set at the dial.

The usual magnetic compensator, shown in the illustrated embodiment as enclosed within a box 48, may be provided to compensate the directional element against local sources of magnetic disturbance. The magnetic compensator 48 may be of any conventional form and is shown in the drawings as being adjustable from the outside by means of screw-headed shafts 49 and 50 actuating adjustment shafts 51 and 52 over gear trains 35 53 and 54.

In order to insure a correct positional indication under operating conditions where relatively large inclinations of the instrument casing occur, the use of an improved system of directional and follower magnets may be used. The improved form of magnet system is diagrammatically shown in Figure 6.

In Figure 5 it is attempted to illustrate the 45 conditions under which a directional element D and a follower element F operate when an inclination of the axis of rotation 5 of the follower magnet occurs with respect to the true vertical direction. The poles of the magnets are designated in the drawings by letters N and S. Inclinations occur, for example, when the craft is inclined about the longitudinal or lateral axis while the directional element maintains a horizontal position due to its pivotal mounting.

In Figure 5 the vertical axis of the instrument casing is represented by numerals 5-5. I represents the plane of rotation of a follower magnet F shown in this figure as being of rod form. Two further planes II and III normal to each other 60 and to the plane I intersecting are indicated in order to make apparent the movements of the two magnets D and F in space.

Assuming, first, that the axis 5-5 of the instrument casing be maintained truly vertical, it 65 appears that upon turning of the craft in azimuth the magnet D will turn in a plane parallel to the plane I, and the follower magnet F will accurately repeat the movements of the directional magnet D, maintaining a north-south direction.

Assuming that the craft be inclined in a north-south vertical plane, such condition existing, for example, when an airplane ascends or descends while maintaining a north course, it appears that a relative inclination will occur between the di- 70 75 78

rectional magnet D, maintaining a horizontal position, and the follower magnet F, the axis of rotation of which becomes inclined due to its mounting in two bearings. The result of such 5 inclination will be, for example, that the south pole of the directional magnet approaches the north pole of the follower magnet F while the opposite poles are spaced farther apart. It is apparent that such inclination will not affect 10 the accuracy of the directional position of the follower magnet.

Assuming that in a second case a similar inclination occurs while the craft is maintaining a west or east course while being inclined about 15 its lateral axis, such condition existing, for example, during an ascent or descent of a plane maintaining a west or east course, it will become apparent that no inclination between the directional and follower magnets occurs. Accordingly, the indication of an indicator operated by 20 the follower magnet will be accurate.

Assuming, finally, that the craft be inclined about its lateral axis while steering a course other than a north, south, east or west course, a 25 deflection of both the directional as well as follower magnets will occur as will be apparent from the following:

It may be assumed that an inclination occurs 30 between the horizontal plane of the directional magnet D and the plane of rotation of the follower magnet F and that the inclination be such that the south pole of the directional magnet be inclined towards the plane I. It becomes easily 35 apparent that on account of the reduced distance between the south pole of the magnet, designated in this position as D', and the plane I the directional magnet will more strongly attract the north pole of the follower magnet. Assuming at this moment that the earth magnetic 40 field were not present, it appears that the directional magnet D as well as the follower magnet F will move into a position in which the south pole of the directional magnet is closest to the north pole of the follower magnet. In other 45 words, the two magnets will come to rest in the plane in which the inclination has occurred. As this plane of inclination, as hereinbefore explained, is not the north-south vertical plane, it will be understood that, inasmuch as actually the 50 earth magnetic field acts on both the directional as well as the follower magnet, the earth magnetic field will tend to move both magnets out of the alignment with the plane of inclination.

Apparently, in this condition neither the directional magnet nor the follower magnet will 55 be aligned with the earth magnetic field and, accordingly, will not provide a correct directional impulse for actuating an indicator.

In order to overcome this "inclination error", 60 as it may be called, an improved system of directional and follower elements is employed according to this invention. The principle of the compensation for the inclination error is briefly 65 the following:

When, due to an inclination, the directional magnet is deflected from the true north-south direction, a shift in the azimuth- or phase-relation 70 between the directional and the follower magnets is provided for, the phase shift being approximately equal to the deviation error of the directional magnet. This result is accomplished in the following manner:

In the improved magnetic compass a directional or first magnetic element is provided 75 mounted for freedom to turn about, and tilt rela-

tively to, a substantially vertical axis. A second magnetic or follower element is provided mounted for free movement about the said vertical axis in confinement by the first magnetic or directional element. The magnetic elements are made of unequal magnetic strength in order to make the combination responsive to the action of the earth magnetic field, and at least one of the magnetic elements is made of such structure as to set up a magnetic field which is of substantially greater horizontal width than vertical depth. This is accomplished by providing the element with a horizontally extended pole area. As will be hereinafter more fully described, a single magnet may be so shaped as to have a laterally extended pole face, or a similar effect be produced by using a pair of magnets having their poles horizontally spaced.

In Figure 6 the directional magnetic element is shown as being of elongated, more particularly 20 octagonal, shape, tapered towards the poles, thus setting up a magnetic field obviously of greater extension horizontally than vertically. The directional magnetic element is shown as being mounted for tilting and turning movement by 25 means of a pivot 18 resting in a cup 19.

A follower element is shown in the illustrated embodiment as likewise being of such structure as to provide a magnetic field of greater horizontal width than vertical depth, the follower magnet 30 being formed by two horizontally spaced magnets 27' and 27'' preferably shorter than the directional magnet 16' and rotatable with a shaft 28 in bearings 29 and 30. The individual magnets 27' and 27'', constituting the 35 follower member, are arranged with their poles spaced farther apart than the width of the pole area of the directional element. The operation of this improved form of magnetic system is, as follows:

When an inclination occurs, which would cause 40 the hereinbefore explained inclination error, the laterally extended field of the one magnetic system is moved closer to the magnetic field set up by the other magnetic system. The latter 45 system will now be strongly governed in its direction by the proximate part of the magnetic field of the first element and, accordingly, assume a different phase relation with respect to the first element than prior to the inclination. Considering, for example, the pair of follower magnets, it is easily seen that upon a tilt of the directional magnet relatively to the follower element 50 one of the pair of follower magnets will move closer towards, and the other one farther away 55 from, one of the poles of the directional magnet. This pole of the directional magnet will now act strongest upon the closest pole of the shorter follower magnet or, in other words, locally on the one side of the horizontally extending pole area 60 of the follower element thus causing a change in the relative azimuthal or phase relation to cancel the inclination error. By choosing the proper relation between the magnetic power of the first and the second element, this phase shift can be 65 made equal to the deviation of the directional element from the magnetic north-south direction whereby an indicator operated from the follower member will be maintained in the proper direction at all times irrespective of inclinations 70 of the instrument. In Figure 6 a pointer 31 is indicated actuated from the shaft 28 over a train of gears 38, 40, and a shaft 32.

Obviously, the present invention is not restricted to the particular embodiments herein shown and 75

described. More particularly, the improved form of indicator is not limited to the use in connection with a magnetic element for its actuation, but may be combined with any of the well-known direction maintaining devices used in navigation. It is further not indispensable that all the features of this invention be used conjointly since they may advantageously be employed in various combinations and sub-combinations.

10. What is claimed is:

1. In a magnetic compass the combination of a support; a direction magnetic element in the shape of an elongated octagon mounted on said support for freedom to turn about, and tilt relatively to, a substantially vertical axis; a follower member mounted on said support for free movement about said axis, said follower member including two horizontally spaced substantially parallel follower magnets in magnetic confinement by said element; and direction indicating means connected to be moved by said follower member in response to movements of said member about the said axis, whereby said indicating means will be actuated in response to movements of said element in azimuth, unaffected by tilting movements of said support.

2. In a magnetic compass the combination of a first magnetic element having pole faces; a second magnetic element shorter than and magnetically coupled with said first element and having pole faces wider than the first element; means for mounting one of said elements for turning about and tilting relatively to a substantially vertical axis; means for mounting the other of said elements for turning about a substantially vertical axis coaxial with said one element; and indicating means connected to be operated by said other element.

3. In a magnetic compass the combination of a first magnetic element; a second magnetic element including a pair of permanent magnets shorter than, and magnetically coupled with, said first magnetic element, the poles of the pair of magnets being spaced wider apart horizontally than the width of the pole faces of said first element; means for mounting one of said elements for turning about and tilting relatively to a substantially vertical axis; means for mounting the other of said elements for turning about a substantially vertical axis coaxial with said one element; and indicating means connected to be operated by said other element.

4. In a magnetic compass the combination of a support, of a first magnetic element; a second magnetic element longer than and magnetically coupled with said first element and having pole faces narrower than the pole faces of the first element; means for mounting one of said elements on said support for turning about and tilting relatively to a substantially vertical

axis; means for mounting the other of said elements on said support for turning about a substantially vertical axis coaxial with said one element; and indicating means connected to be operated by said other element, whereby upon tilt of said support in a direction other than the magnetic north-south or east-west direction a deviation of the other element from the magnetic north-south direction resulting from such tilt will be counteracted by a change in the phase relation between the two elements.

5. In a magnetic compass the combination with a support, of a first magnetic element; a second magnetic element including a pair of permanent magnets shorter than, and magnetically coupled with, said first magnetic element, the poles of the pair of magnets being spaced wider apart horizontally than the width of the pole faces of said first element; means for mounting one of said elements on said support for turning about and tilting relatively to a substantially vertical axis; means for mounting the other of said elements on said support for turning about a substantially vertical axis coaxial with said one element; and indicating means connected to be operated by said other element, whereby upon tilt of said support in a direction other than the magnetic north-south or east-west direction a deviation of the other element from the magnetic north-south direction resulting from such tilt will be counteracted by a change in the phase relation between the two elements.

6. In an indicating instrument a dial bearing a graduation; a pointer movable about a fixed axis and readable on the graduation of said dial; and a reference member adjustable relatively to said pointer and said dial and bearing an index readable on the graduation of said dial, said reference member bearing two parallel reference lines disposed one at each side of the pointer co-operating with said pointer for indicating maintenance of a predetermined indication by parallelism with said pointer.

7. The combination of an instrument casing; a substantially vertical pivot fixed in said casing; a directional magnet mounted on said pivot for freedom to turn and tilt relatively to said casing; a follower magnet in magnetic confinement by said directional magnet and mounted in said casing for movement coaxially to said pivot, the follower magnet being shorter than the directional magnet but wider at its poles than the directional magnet; and indicating means connected to be actuated by a relative movement of said follower magnet and said casing, whereby a correct directional indication is obtained irrespective of tilting movements of said directional magnet relatively to said casing.

PAUL KOLLMAN. 60
